UNITED STATES PATENT OFFICE.

ROBERT GARVIE, OF HARTFORD, CONNECTICUT.

CLEAN-OUT FOR DRAINAGE-PIPES.

SPECIFICATION forming part of Letters Patent No. 496,561, dated May 2, 1893.

Application filed February 5, 1891. Serial No. 380,318. (No model.)

To all whom it may concern:

Be it known that I, ROBERT GARVIE, of Hartford, in the county of Hartford and State of Connecticut, have invented certain new and useful Improvements in Clean-Outs for Drainage-Pipes, of which the following is a full, clear, and exact description, whereby any one skilled in the art can make and use the same.

The object of my invention is to provide means for getting ready access to a soil or drainage pipe, such as is commonly used in sanitary fittings in a building, without unsoldering the parts, and to this end my invention consists of a tubular body part in combination with a cover and cap, and in the details of the several parts making up the device as a whole, and in their combination, as more particularly hereinafter described and pointed out in the claims.

Referring to the drawings: Figure 1 is a view in side elevation of the device as applied to a drainage pipe, with parts in section. Fig. 2 is a detail top view of the cleanout, with parts broken away to show construction.

In the accompanying drawings the letter *a* denotes a length of soil or drainage pipe, that may be of any ordinary material, *b* a T or like joining piece, one of the branches *b'* looking upward, and in this upturned branch the body part *c* of the cleanout is secured, as by cementing or leading in, the spigot end *c'* of the cleanout fitting a bell mouth *b'* of the branch. The cleanout may be fitted in any desirable position to a pipe looking in any direction, that is, it may fit on top, bottom or side of any pipe joint or coupling part having an opening looking in any convenient direction, and the cleanout is made in the several sizes adapting it to fit upon the different sizes of pipe ordinarily used in a building. The mouth *c'* of the cleanout is flaring, and on the inner side a ground surface *d'* is provided upon which the edges of the cover *e* fit, the cover being ground to place and forming a ground joint at *f*, the angle at which the joint is made, while providing for a close and practically air tight contact, being such as not to cause the cover to stick unduly in the socket. Directly back of the joint an upturned flange or surface *e'* is provided, and upon this the under side of the cap *g* bears when the latter is screwed to place. The cover is provided

with a central stem *e* that projects outwardly through a hole in the center of the cap and forms a guide in screwing the latter to place. 55 This stem extends through a hub *g'* in the cover the edges of which are squared or properly shaped so as to adapt them to be grasped by a wrench or key used to remove or replace the cover. The cap is preferably of a size 60 that enables it to fit completely over the end and has a flange *g* that is threaded upon the inner side to fit upon the threaded exterior surface of the outer end of the body part of the cleanout. 65

It is obvious that any other means of securing the cap to the cleanout may be employed without departing from my invention and I do not wish to be understood as limiting my invention to the engagement of the 70 parts as herein set forth as any means of securing the cap to the body part of the cleanout may be employed and come within the scope of my invention.

In the operation of the device the body part 75 of the cleanout having been secured to a pipe the cover is placed in the outer end and drawn to its seat by screwing on the cap, the stem *e* extending through a hole in the cap forming a guide that seats the cap as well as the cover 80 and prevents any stripping of the thread. When the cap is in place a certain portion of its under surface bears continuously all around upon that portion of the cover which lies directly opposite the joint so as to form 85 a firm seat. The cover is preferably formed of the same material as the body part of the cleanout so that there is no chance for leakage of noxious gases or odors by any loosening of the joint by any unequal expansion 90 and contraction of parts, nor is it necessary to employ any packing device other than that comprised in the parts themselves.

The advantages of my device over those of the prior art are that by reason of the construction when the cap is secured in place with a portion of the cover projecting therethrough an absolute certainty of fit is assured of the cover in its seat thus avoiding the use of packings and the preventing the escape of 100 gases.

I claim as my invention—

1. In a cleanout, in combination with the body part having an interior flaring seat, a

cover having a tapering edge ground to the seat, and a central projecting stem on the outside, a cap provided with a threaded part engaging a corresponding threaded part on the 5 body part of the cleanout, an opening through which the stem e^3 extends, and the device adapted to receive a tool for removing the cover, all substantially as described.

2. In combination with the body part of the 10 cleanout having the flaring cover seat, the cover with a beveled edge adapted to fit the

seat with a ground joint between the surfaces, the screw cap removably secured to the body part outside of the cover and bearing on its under surface upon the outer surface of the 15 cover directly over the joint, and the guide projecting from the center of the cover through the cap, all substantially as described.

ROBERT GARVIE.
